JACOB REEF, JR., OF OLNEY, ILLINOIS, ASSIGNOR TO WILLIAM H. WILLIAMSON, FRANK POWERS, AND HIRAM W. WHITE, OF SAME PLACE.

Letters Patent No. 67,347, dated July 30, 1867.

IMPROVED TRESTLE AND SCAFFOLD SUPPORTER.

The Schedule referred to in these Letters Patent and making part of the same.

TO ALL WHOM IT MAY CONCERN:

Be it known that I, JACOB REEF, Jr., of Olney, in the county of Richland, and State of Illinois, have invented a new and improved Adjustable Trestle; and I do hereby declare the following to be a full, clear, and exact description of the same, reference being had to the accompanying drawings, which are made a part of this specification.

Figure 1 is a perspective view representing my improved trestle as set up for use, and partially extended in height and length.

Figure 2 is a perspective view showing it folded as for transportation.

Similar letters of reference indicate corresponding parts in both views.

My trestle-frame consists essentially of two members, each constituting an inverted right-angled triangle, and adapted to slide one past the other for extension and contraction in length. The legs are also made extensible for adjustment in height, and connected to the upper part of the frame by bolts, so as to fold longitudinally thereon. The triangular form gives to each member of the frame, within itself, great vertical strength, but trestles of this description heretofore made have been found defective in the vertical strength of the connection between the two members.

My most important improvement consists in the combination with the two triangular frames of an extensible bar attached to the vertex or lower part of each inverted triangle, forming a tie to prevent the spreading of the legs, and thus afford secure vertical support to the centre or junction of the two members of the frame.

In the drawings, A A' represent the top bars; B B' the posts or legs; C C' transverse beams connecting and bracing each pair of legs; D D' the bottom bar connecting the cross-beams C C' at their centres, and E E' diagonal braces connecting the cross-beams C C' with the top bars A A'. The top bars A A' are adapted to slide one upon the other, as also the two lower tie bars D D', and the two parts B B' of each leg, and these corresponding parts are coupled together by metallic bands *a a*, secured upon the extremity of one part and clasping around and sliding upon the other. Pins *p p* are provided to fix the frame at the required degree of extension. The crossed braces E E' are adapted to freely pass each other vertically and longitudinally when the trestle is undergoing adjustment, and at their upper extremities are attached to the under side of the bands surrounding the top bar by hinges admitting of vertical motion, in order that said braces E E' may be folded up against the under side of the top bars A A' for transportation. At their lower extremity the diagonal braces E E' are stepped in notches cut in the outer upper edge of the cross-beams C C', having shoulders bearing against the inner edge of the cross-beams to give them greater firmness under heavy pressure from above. They are further fastened to the cross-beams by the pins *t t*. The extremities of the top bar A A' are firmly fixed between the upper extremities of the legs B B', one part of the bar A being fixed between the ends of one pair of legs, and the other part, A', being attached in like manner to the other pair of legs. Of the legs, composed, as before described, of two parts sliding on each other, the inner part is the one attached to the top bar by bolts G, and the outer piece slides up and down upon the inner, forming the extension piece, and resting on the ground when the apparatus is extended. The cross-beams C C' are made of the proper length to give the frame the requisite stability. It will be observed that the parts A E B and A' E' B' form two independent triangular frames, each possessing great intrinsic strength, and adapted to be adjusted in relation to each other without having their sustaining capacity impaired, as hereinafter explained.

The operation of this instrument is exceedingly simple: Withdraw the pins *p p* in the top and bottom bars and pull the triangular frames of the trestle apart to the required extent, then insert the pins again, passing each pin through the two corresponding parts. Then remove the pins *p p* in the legs B B' and elevate the triangular frames together with the tie bars D D' to any required height, and again insert the pins, passing them through both pieces that compose the leg as before, and the instrument is ready for use in the new condition. The braces E E' support the extremities of the respective top bars A A', and when the trestle is extended longitudinally the adjustable tie bars D D', connecting the lower parts of the two triangular frames, prevent their spreading, and thus entirely obviate the weakening of the device by its extension.

Among other advantages of this improved instrument are the following: First, its original cheapness of

construction. In one hour any ordinary mechanic can saw out the various pieces for two of these trestles, fit them, bore holes, &c., and any blacksmith can put them together with good strong iron bands, wrought-iron hinges, and bolts at small cost. Second, its simplicity. There is no multiplicity of screws, taps, and wrenches; no slots and combination of two pieces of timber in one; no braces to be adjusted; no uprights distinct from the legs, nothing but timber, bands, holes, and pins. Repairs therefore will be simple, and can cost but a trifle. Third, strength. As the timber is solid and not cut out in the centre, or at the ends where the legs are jointed, while the parts of the legs mutually brace each other, and as the weight on the pins presses perpendicularly and without leverage, a glance will show its superior advantages in this respect. Fourth, portability. By removing the bottom bar and throwing up the braces E E' from their notches the legs B B' fold longitudinally against the sides of the top-bar, being attached to said top bar by bolts through the side, upon which they hinge, but which afford firm lateral support to the legs. The pins *t*, confining the bottom of the braces E E', are made to pass through the ends of the bottom extension bar D D', one set of pins thus answering as fastenings for both braces and the bars. Being folded in this manner the apparatus can be readily taken through doors and windows, and can be carried with other articles, such as lumber, sash, &c. Fifth, perfection of movement. This trestle can be extended further, in proportion to its size, than any other device of the kind in use. When elevated it gains its own height minus the width of the two bands of metal. Thus a six-foot trestle, on elevation, will stand eleven feet six inches at least. When elevated the width of its base is proportionately increased, so that it stands with equal firmness at every elevation. When adjusting the trestle for different elevations the crossed braces adjust themselves. They are always in place and need no attention. By attaching the two bands *a a* of each extensible leg B B', one to the upper end of the lower member B', and enclosing and sliding on the upper member, the other to the lower end of the upper member B, and enclosing and sliding on the lower member, they form their own stops in extending the legs to their extreme length, guide the sliding leg with little friction throughout its motion, and support it against lateral strain.

Having thus described my invention, what I claim as new, and desire to secure by Letters Patent, is—

1. The extensible tie bar D D', when used in combination with the sliding bars A A', legs B B', and diagonal braces E E', as and for the purposes set forth.
2. The legs B connected to the bars A A' by bolts G, affording rigid lateral support, and adapted to fold longitudinally against the bars as represented.
3. In combination with the sliding legs B B' of a trestle of the construction described, I further claim the two bands *a a*, one attached to the upper end of the sliding leg B' and enclosing the leg B, the other attached to the lower end of the leg B and enclosing the leg B', as and for the purposes set forth.

JACOB REEF, JR.
